BUTTER SERVING MACHINE

Sherman A. Thomas, Rochester, N. Y.

Application November 25, 1940, Serial No. 366,942

7 Claims. (Cl. 31—13)

This invention relates to butter serving machines and has for its principal object to provide a novel construction for such machine which will make it simple and fool proof in its manipulation and accurate in its operation.

A further object of this invention is to provide the butter serving machine with an automatic resetting mechanism for the butter feeding mechanism.

Another object of this invention is to provide a butter serving machine in which the resetting of the feeding mechanism automatically takes place during the opening of its cover prior to the reloading of the feeding tube.

Another object of this invention is to house the operating mechanism of the machine adjacent a combined cooling and butter storage compartment in such a manner that the cooling of the butter and its feeding and cutting mechanism will be constant and at the proper working temperature of the butter.

Another object of this invention is to mount the feeding and cutting mechanism of the machine on a base plate and a movement plate in the otherwise non-rigid cover and bottom structure of the machine and spacely connect these plates in a novel manner to permit the compression of the butter without distorting the base of the housing or its cover.

Another object of this invention is to elevate the extruding and cutting mechanism above the bottom of the combined cooling and storage compartment and adjacent the front thereof so as to counterbalance the operating mechanism with the combined cooling and storage compartment and its contents and at the same time provide for the convenient deposit of the butter patty.

A further object of this invention is to provide a floating suspension for the butter feeding mechanism.

Still another object of this invention is to provide the connecting members between the base plate and movement plate of the machine with locking means with which the cover of the machine is automatically locked and unlocked on the housing thereof.

All these and other objects and attendant advantages of this invention will become more readily apparent from the detailed description thereof which follows, reference being had to the accompanying drawings in which

Figure 1 is a top plan view of the mechanism carrying portion of the butter serving machine.

Figure 2 is a front elevation of the machine.

Figure 3 is a top plan view of the machine with the cover in its open or raised position.

Figure 4 is a longitudinal sectional view of the machine taken on the line 4—4 in Figure 3.

Figure 5 is a vertical sectional view of the machine taken on the line 5—5 in Figure 1.

Figure 6 is a detail bottom plan view taken on the line 6—6 in Figures 5 and 7.

Figure 7 is a detail sectional view of the feeding mechanism taken on the line 7—7 in Figures 5 and 6.

Figure 8 is an enlarged sectional view of the pawl mechanism which is operated to advance the piston rod in feeding the piston to extrude a butter patty.

A butter serving machine to be practical and efficient must be simple and fool proof in its manipulation and accurate in its operation. This is true of the machine forming the subject matter of my present invention which embodies improvements over my prior Patent No. 1,320,293, dated October 28, 1919, that overcome the defects in this type of machine which, up to the present, have prevented the universal adoption and use of the machine.

In the formation and extrusion of butter patties, it has been found that butter when compressed acts very much like a rubbery substance, that is, it yieldingly resists its compression during extrusion so that it is absolutely essential that the feeding mechanism and its mounting provide an absolutely accurate non-yielding movement for a predetermined accurate extrusion of each butter patty. It is furthermore essential that the butter be kept at all times at a uniformly proper cutting and spreading temperature, so that the feeding and cutting mechanism is operated with the butter neither too hard nor too soft to thus provide a uniform extrusion and formation for the butter patty and a uniform cutting thereof.

The manipulation of the butter serving machine has been improved over the prior art by providing means whereby the feeding piston is automatically released and retracted for the reloading of the feeding tube, and the retracting means cooperate with the connecting members between the supporting base plate and the movement plate of the machine so that the release of the connection provided by the connecting member and the simultaneous release of the cover of the machine cause the release of the retracting means, which is then free to operate after the adhesive force between the piston and the residual butter in the butter feeding tube has

been broken by the preliminary raising of the piston on the opening of the cover of the machine.

As illustrated in the several figures of the drawings, the housing 1 of the machine is divided into a forward compartment 2 and a rearward compartment 3. The forward compartment has its bottom elevated from the bottom of the rearward compartment to keep the butter feeding tube, which is supported thereon, in a more temperate region of the housing. The housing is made up of an outer and inner sheet metal shell and suitable heat insulation such as cork or other heat insulating material is placed between them to efficiently heat-insulate the interior from the exterior of the housing.

A cover 4 is hingedly mounted on one side of the housing by means of the brackets 5 and 6 and their pivot pins 7 are located so as to provide for a swinging opening movement which will permit the withdrawal by the cover of the piston from any position in the butter feeding tube and provide for ready engagement or disengagement of the cover from the ends of the tie rods 8, 8. The latter are threaded into the base plate 9 and are fixedly held and anchored therein by means of the locknuts 10, 10.

This base plate is located between the outer and inner sheet metal shell so as to provide a strong and rigid base support in the otherwise weak structure of the bottom of the housing. The butter feeding tube 11 is supported by and anchored to the base plate which, for this purpose, is suitably recessed at 12 and provided with an opening 13 centrally of the recess to have the shoulder 14 of the tube rest in the recess and fastened therein with the reduced end 15 of the tube extending thru the opening 13 so as to project from the bottom of the housing. Both the recess and the opening are larger than the outside diameter of the feeding tube and its reduced end respectively in order to permit the feeding tube to be adjusted therein for alignment with the piston 16 and piston rod 17 which are suspended from the cover and are adapted to cooperate with the feeding tube to extrude the butter therefrom.

The cover 4 carries the movement plate 18 which, as in the case of the base plate 9 in the bottom of the housing, is set into the cover so as to provide a strong and rigid support for the feeding mechanism in the otherwise weak structure of the cover. The movement plate has three openings therethru. Two of these, indicated by reference numerals 19, 19, are adapted to have the upper ends of the tie rods 8, 8 project therethru and the third opening 20 intermediate the openings 19, 19 is adapted to have the piston rod 17 suspended therein for movement thru the cover 4. Openings 19, 19 are increased in diameter toward the bottom of the cover so as to have the fixed ends of the tie rods or posts 8, 8 readily enter thereinto or move out thereof when the cover is swung closed or swung open.

Each of the tie rods or posts 8, 8 is provided with an annular groove 21 near the top, substantially level with the top of the movement plate 18, and on the movement plate are mounted to swing a pair of notches 22 and 23 which have slotted heads for their engagement into and partially around the annular grooves 21. The engagement of the latches with the tie rods or posts thus simultaneously locks the cover 4 in place on the housing and rigidly holds and supports the

movement plate 18 on the tie rods or posts 8, 8. In this way the movement plate 18 and the base plate 9 are rigidly connected to permit the compression of butter in the butter feeding tube 12 between them without straining or buckling the structurally weak sheet metal bottom and cover of the machine.

The feeding mechanism used in the intermittent or step by step movement of the piston rod 10 and piston is similar to the feeding mechanism illustrated in my prior patent, above referred to, and includes a pawl 24 which is yieldingly and pivotally suspended thru the yoke 25 by the spring 26. The latter is mounted on the fixed pin 27 carried by the upright 28. The teeth 29 on one side of the pawl at the bottom thereof are adapted to engage the teeth 30 on the piston rod 17 and a guiding yoke 31 extends to one side of the pawl 24 at the top and loosely surrounds the piston rod to keep the pawl in position relative to the piston rod for engagement and disengagement with its teeth.

The cam shaft 32 for the movement of the pawl 24 is mounted to oscillate in the uprights 29, 28 and bridges the space between these uprights in which the pawl is held suspended. The cam shaft operates against the roller-supported saddle 34 to depress the pawl and advance the piston rod on an oscillatory movement of the handle 35. The latter is keyed to the cam shaft on the outside of the upright 28.

Cooperating with the pawl 24 is the spring pressed detent 36 which is mounted to slide horizontally in the insert 37 of the movement plate 18. This detent is vertically spaced from the pawl but is operatively connected therewith by the stud 38 which depends from the pawl and engages into the pocket 39 in the top of the detent. The detent carries at the bottom the pin 40, and a spring arm 41 normally urges the detent toward the piston rod for engagement of its teeth 42 with the teeth 30 of the piston rod. The detent thus holds the piston rod against return movement after every advance by the pawl 24 and thus accurately holds the piston to a predetermined advance for each step of its movement.

After the piston rod has been moved its full range and it is necessary to release it for the withdrawal of the piston from the feeding tube, the detent is automatically disengaged from the piston rod on the unlocking of the cover of the machine preparatory to the refill operation. For this purpose the latch 23 is pivotally mounted in the movement plate by means of the stud 43 which rotates in and projects thru the movement plate and carries at the under side the arm 44. The latter extends laterally behind the pin 40 of the detent so that the opening movement of the latch 23 causes the arm 44 to move the pin 40 and force the detent 36 against the pressure of the spring arm 41 out of engagement with the teeth of the piston rod. When this takes place, the stud 38, carried by the pawl 24, is moved with it and simultaneously swings the pawl out of engagement with the piston rod so that the piston rod is free to be returned to its normal starting position.

As illustrated in Figure 5 the piston rod is suspended from a tension spring 45 which is tensioned as the piston is moved for the extrusion of the butter patties. When the spring 45 is under tension it will therefore automatically move the piston rod after its release from engagement with the pawl 24 and detent 36 and after the piston has been freed from its adhesive

contact with the remaining butter in the feeding tube. The adhesion of the butter to the piston is broken when the cover 4 is swung open and raises the piston rod by means of the shoulder 46 which serves as a stop for the head 47 of the piston rod when the latter has reached its lowermost feeding position. Raising the piston rod by means of the cover causes its bottom end to uncover a vent to prevent any suction below the piston hole 48 thru the middle of the piston 16 and permit the links 49 to raise the piston angularly from one side thereof. By the time the piston is withdrawn from the residue butter in the feeding tube and raised out of the feeding tube in the manner described in my prior patent above referred to, the cover has been swung into a substantially vertical position with the piston rod extending horizontally therethru and free to be drawn back thru the cover to its normal starting position in which the piston is held against the underside of the cover ready to again enter the feeding tube for feeding purposes. A tubular housing 50 surrounds the tension spring 45 and the spring is suitably anchored in the cap 51 at the top of this housing.

But two tie rods 8, 8 are used in the connection of the base plate support 9 with the movement plate 18. This is made possible by their substantially diametrical arrangement relative to the axis of the piston rod and butter feeding tube so that the downthrust of the piston rod into the feeding tube is substantially in a common vertical plane with the axes of the tie rods 8, 8. In this way the thrust of the piston rod and piston against the butter in the feeding tube can exert but a straight axial pressure in the feeding tube to thus avoid any lateral pressure which would cause a rocking of the movement plate on the tie rods and a rocking of the feeding tube on the base plate in the absence of a third or fourth tie rod for the connection of the movement plate and base plate. This is an important feature of the present construction because more than two tie rods would obstruct the space surrounding the feeding tube and complicate the locking and unlocking of the cover, which, in order to make the machine practical, must be done quickly, conveniently and with the least effort on the part of the operator.

The base plate 9 not only rigidly supports and holds the feeding tube 11 in its proper position relative to the feeding mechanism carried by the movement plate 18, but it also serves as the support of the cutting mechanism for cooperation with the mouth 52 at the bottom of the feeding tube. As will be seen from an inspection of the figures, the cutting mechanism includes an open ended wire frame 53 which is oscillated by the vertical shaft 54. The cutting wire 55 is stretched across the open end of the wire frame 53 so as to sweep across the bottom of the mouth 52 of the butter feeding tube to sever the portion of the butter extruded therefrom.

Movement for the operation of the cutter frame is provided by the mutilated bevel gears 56 and 57 of which the bevel gear 56 is carried by the cam shaft 32. Movement of the handle 35 for operation of the feeding mechanism thus simultaneously operates the bevel gear 56 which transmits its motion to the bevel gear 57 for the oscillation of the shaft 58 by means of which the bevel gear is pivoted in the cover 4. Shaft 58 carries the clutch member 59 on the under side of the cover and this clutch member is adapted to engage the clutch member 60 carried by the shaft 54. A suitable coil spring 61 which surrounds the shaft

54, rotatably holds the shaft with the cutting frame to one side of the mouth of the feeding tube and at the same time yieldingly supports the shaft so that, when the two clutch members are brought together on the closing of the cover, the shaft 54 will yield until the two clutch members are brought into driving engagement with each other on the movement of the shaft 58. The rigid base plate 9 thus serves to accurately support and guide the cutting frame in its movement across the mouth of the feeding tube during the operation of the machine so that the uniform extrusion of the butter by the accurately operating feeding mechanism is supplemented by an accurate and uniform movement of the cutting mechanism to produce identical butter patties of uniform thickness at every operation of the machine.

As heretofore described, the front portion of the housing in which the feeding mechanism is mounted and operated has its bottom elevated from the bottom of the rear portion of the housing which serves as the cooling and storage compartment. In this latter compartment is provided the removable false bottom 62 which is channeled centrally to have the bottom of the ice chest 63 nest thereinto longitudinally thereof to properly locate and hold the cooling medium in the middle of the compartment and provide substantial storage space for the butter on each side thereof. As is well known the coldest temperature in a housing of this kind will always be found at the bottom of the compartment because the cold air displaces the warmer air. For this reason the front compartment with its raised bottom will be found to be at a higher temperature so that the feeding tube, especially the bottom of it, will not be surrounded by the extremely cold air found in the bottom of the rear or storage compartment. This is important in this machine because it keeps the butter in the feeding tube at a cutting and spreading temperature where otherwise it would be hard and consequently difficult to cut. Air is free to circulate around the butter feeding tube and the ice chest is spaced from it to help in keeping the butter at all times at the proper cutting temperature.

I claim:

1. In a butter serving machine the combination of a housing, a cover removably mounted on said housing, a butter feeding tube within said housing, a piston rod movable thru said cover, a piston carried by said piston rod for movement thereby in said feeding tube, intermittent feeding means carried by said cover and engaging said piston rod, means for locking and unlocking said cover on said housing, and means operated by said locking and unlocking means for causing the engagement or disengagement of said intermittent feeding means with said piston rod.
2. In a butter serving machine the combination of a housing, a removable movement plate on said housing, a butter feeding tube within said housing, a piston rod movable thru said movement plate, a piston carried by said piston rod for movement in said feeding tube with the movement plate in place on said housing, intermittent feeding means carried by said movement plate and movable into and out of engagement with said piston rod and moving the piston rod in one direction, means for rigidly holding said movement plate on said housing to provide for the movement of said piston rod thru said movement plate relative to said feeding tube,

spring means for moving said piston rod thru said movement plate in the opposite direction, and means operated on the release of said movement plate holding means to disengage said intermittent feeding means from said piston rod to provide for the movement of said piston rod by said spring means.

3. In a butter serving machine, the combination of a housing, a removable cover on said housing, a butter feeding tube mounted within said housing, a piston rod movable thru said cover, a piston carried by said piston rod for movement in said feeding tube, intermittent feeding means carried by said cover and movable into and out of engagement with said piston rod and moving said piston into said feeding tube, a movable detent engaging said piston rod to normally hold said piston against movement out of said feeding tube, spring means for movement of said piston rod on the release by said detent, means for locking said cover to said housing, and means operated by said locking means in unlocking said cover for movement of said detent and feeding means out of engagement with said piston rod to provide for the movement thereof by said spring means.

4. A butter serving machine comprising a housing having an undivided combined cooling and storage compartment and an adjacent butter feeding compartment with the bottom of said butter feeding compartment elevated from the bottom of the combined cooling and storage compartment so as to provide an overhanging section on the outside of said housing, a butter feeding tube supported on the elevated bottom and spaced from the walls of the feeding compartment and from the cooling and storage compartment, a mouth in the lower end of said feeding tube and extending thru said elevated bottom of said overhanging section of said housing, a cutting mechanism on the under side of said elevated bottom cooperating with said mouth, and a feeding mechanism including a piston for extruding the butter from the mouth of said feeding tube in said overhanging section of said housing.

5. A butter serving machine comprising a housing having an open top and a closed bottom, a cover closing the open top of said housing, a movement plate carried by said cover, a rigid base plate in the bottom of said housing, a pair of tie rods anchored in said base plate and projecting thru said housing and said cover and movement plate, a pair of locking dogs mounted to swing on top of said movement plate for engagement with said tie rods above said cover so as to hold said cover and movement plate rigidly locked to said tie rods, a feeding mechanism mounted on said movement plate for moving a

piston rod, a butter feeding tube mounted on said base plate within said housing and between said tie rods, a piston movable in said feeding tube, and a piston rod movable by said feeding tube mechanism thru said cover and movement plate for movement of said piston in said feeding tube.

6. In a butter serving machine the combination of a combined feeding and cutting unit comprising a rigid base plate, a rigid movement plate removably supported by said base plate, means for raising said movement plate, locking means for locking said movement plate and said raising means to said base plate, step by step feeding means carried by said movement plate including a piston rod and piston for movement of said piston rod and piston toward said base plate, a feeding tube mounted on said base plate for movement of said piston rod and piston thereinto, holding means carried by said movement plate for engagement of said piston rod to normally hold said piston rod against movement out of said feeding tube, means operatively connecting said locking means and said holding means to provide for the simultaneous unlocking of said raising means and the release of said piston rod holding means at any position of said piston in said feeding tube, and a cutting member carried on the under side of said base plate and operatively connected with said feeding means to cause said cutting member to swing across the bottom of said feeding tube.

7. In a butter serving machine the combination of a housing, a cover for said housing, a base plate in the bottom of said housing, a butter feeding tube mounted on said base plate, a combined tie rod and locking member carried by said base plate for cooperation with said feeding tube and said cover, a movement plate carried on top of said cover for operation thereon, feeding means on said movement plate including a piston rod and a piston mounted to swing on said piston rod, latch means carried by said movement plate for locking engagement with said combined tie rod and locking member to provide a rigid connection between said base plate and said movement plate to permit the extrusion of butter under pressure by said piston of said feeding means from said feeding tube, and pivoted means on said cover arranged relative to said combined tie rod and locking member and said piston in said feeding tube to provide for the simultaneous release of said combined tie rod and locking member from said movement plate and the release of said piston in said feeding tube for free movement of said piston out of said feeding tube on the movement of said cover away from said housing.

SHERMAN A. THOMAS.
